(57) **CLAIM**

The ornamental design of a fragrance diffuser as shown and described.

DESCRIPTION

FIG. 1 is a perspective view of a fragrance diffuser showing our new design.

FIG. 2 is a first side view thereof.

FIG. 3 is a second side view thereof, showing the fragrance diffuser rotated 1/4-turn relative to the first side view.

FIG. 4 is a top view thereof.

FIG. 5 is a bottom view thereof; and,

FIG. 6 is a perspective view of the fragrance diffuser in an environment of use with liquid in both the top and bottom container portions of the fragrance diffuser.

The broken lines illustrate portions of fragrance diffuser that form no part of the claimed design. Additional broken lines in FIG. 6 show environmental subject matter and form no part of the claimed design.
